SAFETY HELMET

Morrill Dakin, Concord, N. H., assignor to General
Motors Corporation, Dayton, Ohio, a corpora-
tion of Delaware

Application July 29, 1939, Serial No. 287,323

5 Claims. (Cl. 128—145)

This invention relates to hoods or head covering devices intended for use by persons engaged in occupations requiring them to be exposed to an atmosphere laden with foreign particles.

In many occupations, it is necessary for persons to work in contaminated atmospheres, thus requiring them to enclose their heads within some form of hood or helmet to prevent inhalation of quantities of foreign particles or undesirable fumes or gases. Since the head of the person is entirely enclosed, it is necessary to supply the person wearing the hood with an adequate supply of fresh air within the hood, since all of the air breathed by the person comes from within the interior thereof.

The hoods or helmets heretofore used have been heavy, bulky devices which were difficult to wear and would tire the operator. Further, these devices have afforded the operator an extremely limited field of vision, being that obtained through a window provided before the eyes of the operator. The remainder of the body of the hood or helmet has been constructed from an opaque or translucent material.

It is thus an object of my invention to provide a helmet or hood constructed from a lightweight transparent material which will permit an operator to have clear and unobstructed vision in all directions without regard to the particular position of a vision window which may be provided in such hoods.

A further object of my invention is to provide a hood or helmet of such lightweight construction that the helmet may be comfortably supported directly upon the head of an operator without the use of any supporting superstructure, and which may be retained in position upon the head of the operator in such a manner that a vision window, provided in the helmet, is always in alignment with the eyes of the workman.

A still further object is to provide a hood or helmet of such lightweight material that it may be supported upon a cloth cap worn by an operator, the cap having a flexible tube secured thereto through which fresh air is supplied to the interior of the hood when placed over the head of the operator, the hood having means whereby the same can be attached to the visor of the cap, thereby aligning a vision window in front of the eyes of the operator.

Further objects and advantages of the present invention will be apparent from the following description, reference being made to the accompanying drawing, wherein a preferred form of the present invention is clearly shown.

In the drawing:

Fig. 1 is a perspective view of my protective head covering device showing the same in position as worn by an operator;

5 Fig. 2 is a cross section substantially along line 2—2 of Fig. 1;

Fig. 3 is a partial perspective view of the cap and hood showing a modified arrangement of attaching the hood to the visor of the cap; and

20 Fig. 4 is a perspective view of the cap showing a head band adjusting means.

In my protective head covering device, I have provided a cap, which may be constructed from a lightweight flexible material, which is adapted 15 to be worn upon the head of a wearer or operator. I have also provided a hood covering which is adapted to be positioned over the head of the wearer of the cap. This hood is constructed from a very lightweight, transparent material and is 20 of such lightweight construction that it may be supported upon the crown of the cap as worn by the wearer. This transparent or semi-transparent hood will afford the wearer of the device a complete field of vision about himself, which field

25 is normally obscured by the opaque or translucent type head covering devices previously known in the art. In order to afford the person wearing my hood a perfectly undistorted field of vision before himself, a semi-rigid vision window is provided in a depending wall of the hood. This vision window is of a clear, transparent material which will afford a very clear and undistorted field of vision in front of the wearer of my device. In order to supply the wearer of the hood 30 with an adequate supply of fresh air, a tube is cured to the cap through which a supply of fresh air is continuously delivered from a suitable source of supply and exhausted within the interior of the hood near the face of the wearer of my device.

More specifically, my device consists of a flexible body portion 10 which comprises a cap or hat to be worn by a workman required to follow his 45 occupation in areas contaminated with foreign particles or undesirable fumes or gases. This cap or hat is preferably made from a soft, flexible material, such as cloth, which is light in weight, and will rest comfortably upon the head of the workman. The cap 10 is provided with a rigid 50 visor 11 extending from the front portion of the cap. This visor shields the eyes of the workman from glaring overhead lights, and is adapted to direct a flow of fresh air, discharged from suitable supply tubes, over the face of the workman. 55 Flexible tubes 12 and 12a are attached to the

lower edge or periphery of the body portion of the cap 10. These tubes are positioned along either side of the cap 10 and encircle the greater portion of the cap. One end of the tubes 12 and 12a terminate on each side of the visor 11, as indicated at 13 and 14, and below the bottom face of the visor 11. These tubes 12 and 12a may be joined together at the rear of the cap by means of a connecting member 15. This member 15, as shown in Fig. 1, consists of a metal T-connection. The through portion of the T-connection is attached to one of the ends of each of the portions of tubes 12 and 12a. The T portion extends into a flexible tube 16. This tube 16 is adapted to be connected to a suitable source of fresh air supply which may deliver air under pressure through the tube 16 and into the tubes 12 and 12a. The air will exhaust from the tubes 12 and 12a near the front edge of the cap 10 and under the visor 11. The means for delivering a continuous fresh air supply to the interior of the hood or head covering device is thus entirely supported by the cap 10 and is independent of the head covering or hood which is adapted to be placed over the head of the workman.

The head covering or hood 20 is constructed from a material which is transparent or semi-transparent, such as a rubber hydrochloride product or oiled silk, and which is flexible and very light in weight. The hood is comprised of a crown portion 21, which is substantially triangular in shape, the base of the triangular portion being positioned toward the front of the hood structure. A depending wall or body portion 22 is provided for the hood 20 and is adapted to be attached to the crown portion 21 by sewing or stitching the same along the edge of the triangular crown-shaped section, as indicated at 23 and 24. This depending wall portion 22 is also sewed or stitched along the back edge 25, thereby closing the structure and forming a complete head covering or hood. A flexible neck band 26 is provided around the circumference of the bottom edge of the hood structure. This neck band 26 is adapted to retain the open end 45 of the hood structure firmly about the neck and shoulders of the person wearing the device.

Since my protective head covering device is constructed from a material which is transparent or at least is semi-transparent, it is thus noted that a person wearing the hood will be afforded with an unlimited field of vision about himself and may look freely on all sides. However, long usage of a material which is flexible in nature may have a tendency to cause the material to wrinkle. These wrinkles may, in time, have a tendency to blur the field of vision for the person wearing the hood or protective head covering device.

In order to afford a field of vision in front of the person which will not become blurred during use of my device, I provide a window in the depending wall 22 of my hood 20. This window includes a vision member 30 of transparent material such as sheet Celluloid or a sheet of regenerated cellulose which is free from distortion defects in order to afford clear vision therethrough. The window vision member is supported in an opening provided in the depending wall 22 of my hood 20 by means of a frame 31. This frame consists of two sheets of a thin semi-rigid 70 material which may be either transparent or opaque, as deemed necessary. These sheets of material 32 and 33 are stitched together along three of the outer edges thereof. When fastening sheets 32 and 33 together by the stitching 75

34, the edge of the crown 21 of my hood and the edge of the opening in the depending wall 22 are secured between the sheets 32 and 33 by the stitching 34, thereby providing a means for retaining the frame 31 in position in the depending wall 22 of my hood structure. As previously stated, the frame 31 is stitched along three edges thereof. The fourth edge 35 of the frame structure is permitted to remain open, so that the vision member 30 may be removed and replaced from between the sheets 32 and 33 of the frame 31. This removable feature of the vision member is particularly useful in view of the fact that after considerable use of my hood, the vision member may become fogged or scratched in such a manner as would impair the vision of the workman wearing the hood. The fogging of the vision member would require the replacement of the entire hood if the vision member itself could not be replaced. The edge of the opening in depending wall 22 adjacent the open side 35 of the frame 31 may be secured to the inner sheet 33 of the frame 31 by stitching the same to that frame or cementing the same thereto, or by any other suitable means of attachment.

In normal use of my protective head covering device, the cap 10 may first be placed upon the workman's head. In order to provide a cap which will comfortably fit the head of the workman, I provide means to permit adjustment of the head band size. The adjusting means as shown in Fig. 4 consists of a cloth tab 60 which is attached at one end to the head band portion of the cap 10. The free end of the tab 60 is provided with one portion 61 of a snap button. The cooperating portion 62 of the snap button is attached to the head band portion of the cap 10. Several of the snap button portions 62 can be attached to the cap to permit considerable adjustment of the head band size of the cap 10. After the cap has been comfortably adjusted upon the head of the workman, the hood 20 may then be placed on the workman's head. Since the hood 20 is of very lightweight structure, the crown 21 of the hood 20 may support the hood upon the cap 10 when in position upon the head of the workman. I am able to permit a support of my hood structure 20 in this manner in view of the fact that the hood structure is of a very lightweight material which will not rest in a heavy manner upon the head of the workman and tire him after wearing the same for a period of time. When the hood 20 is in position upon the head of the workman, fresh air is admitted to the interior of the hood through the tube 16 and tubes 12 and 12a. This fresh air is discharged from the ends 13 and 14 of the tubes 12 and 12a in a forward direction and below the lower surface of the visor 11. Since the air is delivered below the visor 11, a clean, fresh current of air will be continuously circulated over the face of the workman. The excess air will exit from the neck opening around the neck and shoulders of the workman, since the elastic neck band 26 is not so tight as to prevent the air from exhausting from between the body of the workman and the elastic neck opening 26.

In order to provide a convenient means for retaining the vision window member 30 in front of the eyes of the workman, at all times, after the hood has been placed upon the workman's head, I have provided two U-shaped clips 40 and 41. These clips are attached to the upper edge of frame 31 by means of rivets 42, or any other suitable attaching means and are directed inwardly into the interior of the hood 20. The clips 40 and

41 are provided on either side of the frame 31 and are spaced sufficiently far apart to engage opposite edges of the visor 11. The stiff visor 11 of my cap 10 is adapted to extend into the mouth of the U-shaped clips 40 and 41 and be retained within the clips by means of friction. The clips thereby provide a means for retaining the vision window member 30 in a definite location with respect to the cap 10, and thus with respect to the eyes of the person wearing the hood 20, regardless of the amount of movement the person may be required to do while performing his normal working functions. While these clips are not necessary from the standpoint of supporting my hood 20 upon the head of the person wearing the same, they are convenient from the standpoint of retaining the hood in a predetermined location upon the cap 10.

In Fig. 3, I have shown a modified arrangement whereby my hood 20 may be attached to the visor 11 of the cap in order to retain the vision window member 30 in a definite position with respect to the cap. In this arrangement, I attach two flexible tabs 50 and 51 to the top edge of the frame 31. These tabs may be attached in any suitable manner, such as by riveting the same to the frame 31 and are spaced sufficiently far apart as to align with opposite edges of the visor 11 of my cap 10. On the free end of the tabs 50 and 51, I provide one-half of a snap button which is adapted to coact with the opposite half of the snap button attached to the visor 11 of the cap 10. The portions of the snap buttons attached to the visor 11 are attached adjacent opposite edges of the visor, so that when the portions of the snap buttons on the tabs 50 and 51 engage the portions of the buttons on the visor, the hood 20 will be secured in a definite relation with respect to the cap 10. This arrangement retains the vision window member 30 in a definite relation to the cap 10 and to the eyes of the workman wearing the cap and hood.

It will be understood that the fastening means 40 and 50 for attaching my hood 20 to the cap 10 are not essential in providing a support for my hood 20 upon the cap 10, since the hood 20 is of such lightweight, transparent structure that it may readily support itself upon the cap in position over the head of a wearer of the cap. However, these fastening means 40 and 50 are useful in that they provide a means for always maintaining alignment of the vision window member 30 with respect to the eyes of the person wearing my head protective covering device, so that the vision window member 30 will always be in front of the eyes of the person, regardless of the movement of the head of the person while working.

It will thus be seen that I have provided a helmet or head covering device which affords a person wearing the device a complete field of vision about himself at all times, since the hood or head covering is constructed from a material which is transparent or at least semi-transparent. Also, my protective head covering device is very light in weight, since the material from which it is constructed, such as oiled silk or a rubber hydrochloride product, are light in weight.

The transparency of my head covering device is particularly advantageous where it is necessary for the workman to be engaged in localities requiring him to be careful of the welfare of other persons, and in watching moving objects so that he will not be injured by the same. The transparent hood also permits the workman to have sufficient vision to watch all of the activities

about himself, thereby reducing the accident hazard which has heretofore been present when using head covering devices having an opaque or translucent type hood or head covering. Further, this transparency of the head covering or hood reduces to a minimum the effect of shadows by the head covering or hood upon the work being done by the person wearing the device, thereby affording better lighting conditions upon the work and consequently better vision by the workman wearing my head covering or hood. By virtue of the triangular shape of the hood, only three main seams are required for its manufacture. This shape is very desirable since the triangularly shaped crown provides a wide front to accommodate the window and prevents bulkiness at the rear. A hood of this shape requires less material for its manufacture and is more comfortable than the four-sided hoods or circular hoods.

While the form of embodiment of the present invention constitutes a preferred form, it is to be understood that other forms might be adopted, all coming within the scope of the present invention.

What is claimed is as follows:

1. A protective head covering device comprising a flexible cap provided with a visor, a flexible tube secured to the periphery of the bottom edge 30 of the body portion of said cap, said tube having an end terminating at each side of the visor of said cap, a flexible supply tube communicating with said tube on said cap and adapted to extend downwardly from said cap and be supported by said cap, and a transparent hood adapted to envelop said flexible cap and be supported thereby.

2. A protective head covering device comprising a flexible cloth cap having a visor, a flexible transparent hood adapted to envelop the head 40 of a person wearing the cap and be supported upon said cap, said hood having a loosely fitted neck opening, a flexible tube secured to the periphery of the body portion of said cap and having the open ends thereof adjacent opposite sides 45 of the visor, and a flexible air conducting tube extending into said hood and communicating with said first mentioned tube.

3. A protective head covering device including a flexible cap adapted to be worn by an operator, 50 a hood comprising a flexible substantially triangular-shaped crown portion and a flexible body portion secured to said crown portion, a window having a frame secured to said body portion and to the base of said triangularly shaped crown portion and a transparent vision member carried by said frame, said hood being adapted to be supported upon said cap when being worn by an operator, and means for admitting fresh air within said hood.

4. A protective head covering device comprising a flexible cloth cap having a body portion and a visor, a flexible transparent hood adapted to loosely envelop the head of a person wearing the cap and be supported upon said cap, said hood having a loosely fitted neck opening, a flexible tube carried by said cap adjacent the periphery 65 of the body portion of said cap and having means for discharging air into said hood, a flexible air conducting tube extending into said hood and communicating with said first mentioned tube, window means including a substantially rigid transparent portion and means for mounting said transparent portion in the front wall of said hood, and a disconnectable connecting and locat-

ing means between the visor and said window means for locating the transparent portion of the window directly in front of the face of the wearer.

5. A protective head covering device comprising a flexible cloth cap having a body portion and a visor, a flexible transparent hood adapted to loosely envelop the head of a person wearing the cap and be supported upon said cap, said hood having a loosely fitted neck opening, a flexible tube carried by said cap adjacent the periphery of the body portion of said cap and having means for discharging air into said hood, a flexible air conducting tube extending into said hood and

communicating with said first mentioned tube, window means including a substantially rigid transparent portion and means for mounting said transparent portion in the front wall of said hood, and a disconnectable connecting and locating means between the visor and said window means for locating the transparent portion of the window directly in front of the face of the wearer, said means for discharging air into said hood including means to discharge the air towards said window means.
